UNITED STATES PATENT OFFICE.

THOMAS CARROLL, OF DAYTON, OHIO, ASSIGNOR, BY MESNE ASSIGNMENTS, TO THE NATIONAL CASH REGISTER COMPANY, OF DAYTON, OHIO, A CORPORATION OF OHIO (INCORPORATED IN 1906).

KEYBOARD MECHANISM FOR REGISTERING-MACHINES.

No. 909,866.

Specification of Letters Patent.

Patented Jan. 19, 1909.

Application filed December 16, 1905. Serial No. 291,973.

To all whom it may concern:

Be it known that I, THOMAS CARROLL, a citizen of the United States, residing at Dayton, in the county of Montgomery and State of Ohio, have invented certain new and useful Improvements in Keyboard Mechanisms for Registering-Machines, of which I declare the following to be a full, clear, and exact description.

10 This invention relates to improvements in keyboard devices for registering machines, such as cash registers, adding machines and the like, and has among its objects to provide a detent mechanism which will serve 15 to latch an operated key in depressed position and at the same time unlock a register controlling device, this mechanism being combined with another device which will prevent misoperation or manipulation of the 20 first mentioned mechanism.

With these and incidental objects in view, the invention consists in certain novel features of construction and combinations of parts, the essential elements of which are set 25 forth in appended claims and a preferred form of embodiment of which is hereinafter specifically described with reference to the drawings which accompany and form part of this specification.

30 Of said drawings: Figure 1 represents a sectional view of the keyboard of a cash register to which these inventions are applied, showing one of the registering elements and the latching detent plate, together with parts of the operating mechanism. Fig. 2 represents a detail view of a stop plate coöperating with the registering element. Fig. 3 represents a detail sectional view of the keyboard showing a locking 35 plate for effecting the locking of the operating mechanism of the machine when one of the keys is improperly operated; and Figs. 4 and 5 represent detail views of certain operating cams carried on one of the 40 main driving shafts of the machine.

45 Referring to said drawings, the keys 10 are arranged in the usual form of vertical columns, one column or bank for each amount digit or other divisional use to which the 50 keys may be applied. These keys are inserted through the usual apertures in the keyboard and are spring-pressed outward by the usual springs 11 to retain the keys normally in 55 outward position. Each key has projecting from its side a pin 12. Coöperating with each bank of keys is a differentially movable element 13 which may be either a register controlling element or a recorder controlling element to effect the registration of various amounts or effect the printing of certain 60 insignia according to the differential movements of the element 13. In the present instance this element 13 will be referred to as the registering lever, this lever being formed with teeth at its upper end meshing with a 65 gear wheel 14 which in turn operates a suitable counter 15 by a mechanism not necessary to describe here since it constitutes no part of the present invention. This registering lever 13 also has at its upper end a pin 16 70 which is normally engaged by a nose 17 of a detent plate 18. The lever 13 is pivoted upon a transverse shaft 19 and a spring 20 coiled around this shaft and bearing against a rearwardly projecting foot 21 of the lever, 75 normally tends to throw the upper end of the lever rearward, but the engagement of the detent plate 18 with the pin 16 holds the lever from such rearward movement. The detent plate 18 is formed with a series of 80 heads, one for each key, each of these heads having a beveled surface 22 which lies in the path of the key pin 12. This beveled edge ends in a recess 23 so that when any key is pressed in, the action of the pin 12 against 85 the beveled edge forces the detent plate downward against the tension of its compression spring 24, and as soon as the pin reaches the recess 23 the detent plate snaps back slightly to latch over the pin 12 and thus latch the 90 key in depressed position. Thus the detent plate 18 is moved downward a certain extent under the key action, and then moves upward slightly to effect the latching of the key, but the ultimate position of the detent 95 plate is to such an extent below its normal position that the nose 17 is withdrawn from the path of the pin 16 and thus the registering lever 13 is free to spring rearward. The registering lever springs rearward differentially according to whichever key in this bank is depressed. This is effected by means of a stop plate 30 which is connected at its lower end with the aforesaid foot 21 of the registering lever, so that as the lever springs rearward, this stop plate will be drawn longitudinally.

100

105

dinally downward along the keyboard, the stop plate 30 being situated side by side with the registering lever 13 and detent plate 18 so that the various stop projections 31 of the 5 stop plate may coöperate with the same key pins 12. These stop projections are differentially arranged with reference to their respective key pins so that when any key is depressed the stop plate may slide down a 10 certain distance before its corresponding projection strikes the key pin to arrest the rearward movement of the registering lever 13. By this means the depression of any key, 15 sets the registering lever 13 differentially according to the position of the key in the bank.

In order to operate the detent plate 18 to release the operated keys by the operation of the machine, a rock shaft 40 is provided. 20 This shaft has projecting forward from it a series of arms 41, one for each detent plate of the various banks, these arms having jaws engaging a pin 42 formed on a rearward projection on the detent plate whereby to shift 25 the detent plate at the proper time to unlatch the operated keys and permit the same to return to normal outward position. Projecting rearward from said shaft 40 is a pawl 43 formed with a nose 44 lying in the path 30 of a releasing cam 45 fast upon the side of a locking disk 46 (see also Fig. 5), the purpose of which disk will be presently described. This disk 46 is fast upon a shaft 47 which constitutes one of the main driving shafts of 35 the machine and may be operated by means of any suitable gearing from the main operating handle of the machine, such mechanism not being necessary to describe herein. When this shaft 47 is turned in the direction of the 40 arrow in Fig. 1, the cam 45 strikes the nose 44 of the arm 43 and rocks the arm 41 downward so as to shift the detent plates 18 downward against the tension of their springs, and thus release the depressed keys. Also 45 depending from and fast to the rock shaft 40 is a locking arm 50 carrying at its lower end a lug 51. This lug projects laterally into alinement with the locking disk 46. When any key is depressed, the downward movement 50 of the detent plate 18 will act through the arm 41 to rock the shaft 40 to throw the lug 51 toward the locking disk 46. When the key pin 12 is passing over the extremity of its beveled nose, the shaft 40 is rocked to 55 such an extent that the lug 51 will be carried underneath the shoulder 52 formed on the locking disk 46, thus locking the shaft 47 and the machine from operation. As soon however, as the detent plate has settled back 60 slightly to latch the key in depressed position by the engagement of the recess 23 over the pin 12, this carries the lug 51 again slightly forward so that it stands just free of the edge of the locking shoulder 52 and thus is 65 in position to permit the machine to be oper-

ated. When the shaft 47 has been revolved far enough to cause the cam 45 to operate the nose 44 and thereby rock the shaft 40 to release the keys, the locking disk 46 is at such point brought into position that it is no 70 longer in the path of the lug 51, and hence the arm 50 can spring rearward far enough to permit this releasing movement of the detent plate 18.

Since the ultimate position of the detent 75 plate 18 when any key is depressed, is with the recess 23 engaging the key pin 12, the nose 17 of the detent plate is retracted downward far enough to unlock the registering lever 13 as above described. In 80 this situation, however, the registering lever 13 is not yet allowed to drop, being held up by a restoring bar 60 which engages on the rearward side of the lever near its lower extremity. This bar is reciprocated at each 85 operation of the machine, being first withdrawn rearward sufficiently to permit such of the registering levers as have been released, to drop to their differential positions, and then the restoring bar is returned to 90 normal forward position whereby to return all of the registering levers also to normal forward position. The exact means for operating such a restoring bar it is not necessary to describe herein since in itself 95 it does not form part of the present inventions except insofar as it lends points of advantage to the present improvements. From this construction it will be apparent that even though a key in a certain bank 100 has been pressed in, its registering lever will not drop although the nose 17 of the detent plate is removed from the path of the pin 16. Therefore if a mistake has been made in the pressing in of a key in this 105 bank, this key may be released by simply tapping another key in this bank to operate the beveled detent plate sufficiently to release the formerly depressed key, this being an example of the so-called "flexible keyboard". If however, a key were pressed in not quite to the full extent of carrying 110 its pin 12 along the beveled edge 22, the detent plate would by this means be moved downward sufficiently to withdraw the nose 115 17 from engagement with the pin 16, this position of the plate 18 being the same in downward extent as if the pin 12 were engaged by the recess 23. When the key and plate are in this position just described, the registering lever 13 would be unlocked but the key would not be latched in depressed position; therefore upon the operation of the machine, with the withdrawal of the restoring bar 60, this registering lever would drop and then the key might be pulled out or allowed to spring back to its normal outward position and apparently from the looks of the keyboard no registration would have been entered whereas in 120 125 130

reality by this careless operation or mis-operation, the registering lever would have dropped to its fullest extent and would have made an entry in the machine. To prevent any such misoperation, a locking plate is provided as shown in Fig. 3. This locking plate 70 is also mounted side by side with the other plates and is formed with a series of noses 71. Projecting rearwardly from the lower extremity of this plate is a foot which is engaged by an arm 72 mounted upon a rock shaft 73, there being one of these arms 72 for each bank of keys. Projecting rearward from this rock shaft 73 (see Fig. 1) is an arm 74 having a locking nose 75 as its rearward end. Mounted upon this arm 74 is a pawl 76 which is normally spring-pressed upward by a compression spring 77 also mounted upon the arm 74. This pawl 76 has an upwardly extending nose which is in alignment with a cam disk 78 (see also Fig. 4) which disk is fast upon the aforesaid shaft 47. Fast upon the disk 78 is a locking plate 79 which stands in alignment with the locking nose 75 of the arm 74.

Upon the initial operation of the machine, the rotation of the shaft 47 causes the disk 78 to act against the pawl 76 and force the same downward. This pawl through the spring 77 then acts upon the arm 74 to rock the shaft 73 which in turn rocks the arm 72 to carry each of the locking plates 70 upward. In the normal outward and unoperated position of the keys, the key pins 12 stand forward of the various locking noses 71 of the locking plate so that the plate is free to be reciprocated upward in this manner. Also if any key is completely depressed, the shape of the enlarged recess below the corresponding nose 71 is such that the plate 70 can still be reciprocated upward without hindrance. When however, any key is partially depressed in the manner above outlined so as to carry it inward in order sufficiently to move the detent plate 18 downward to unlatch the registering lever 13 without moving the key pin far enough inward to be latched by the detent plate, this partial depression of the key will, as shown by the key 80 in Fig. 3, bring its key pin directly into the path of the corresponding nose 71 of the locking plate. In such a situation if the machine is started in its operation and the shaft 47 begins to revolve, the disk 78 will, as before, press against the pawl 76, but the arm 74 cannot now move downward because the locking plate 70 is held locked against the key pin. Therefore the pawl 76 is simply depressed against the compression of its spring 77. However since the arm 74 has not now been depressed, this leaves the locking nose 75 still in the path of the locking lug 79 so that the lug locks against said nose and the

machine is securely locked against further operation and cannot be completely operated until the partially depressed key is fully returned completely to normal outward position or completely to normal inner 70 position. A suitable spring 81 tends to restore the arm 74 and locking plate 70 to normal lower position. From the shape of the disk 78 (as shown in Figs. 1 and 4) it will be seen that the arm 74 will be held 75 downward and the locking plate 70 will be held shifted upward over only a small portion of the revolution of the shaft 47. As soon as the disk 78 is rotated so that the enlarged portion thereof is carried beyond the 80 pawl 76, the arm 74 is free to return to upper position and the locking plates 70 to normal lower position. This is timed to occur before the latching detent plate 18 is shifted downward to release the keys, so that the 85 locking plate 70 does not in any way serve as a latching plate, but simply performs this locking function to prevent the operation of the machine when any key is only partially depressed sufficiently to unlatch the 90 registering element without at the same time latching the key in depressed position.

While the form of mechanism here shown and described is admirably adapted to fulfil the objects primarily stated, it is to be 95 understood that it is not intended to confine the invention to the one form of embodiment herein disclosed, for it is susceptible of embodiment in various forms all coming within the scope of claims which follow. 100

In a co-pending application, Serial No. 293,091 filed by the same applicant on December 23, 1905, there is shown and described a form of keyboard mechanism having certain features in common with the 105 mechanism shown in the present case, and it is desired that the broad claims common to the subject matter of these two cases shall be contained in the present application. 110

What is claimed is:

1. In a key board mechanism for accounting machines and the like, the combination with a main operating mechanism, of a series of keys and an accounting element controlled thereby, means for normally locking said accounting element, a detent member having provisions for latching said keys in depressed position and for operating said locking means, and means for preventing the operation of the operating mechanism when 115 any key is in a partially depressed position.

2. In a keyboard mechanism for accounting machines and the like, the combination with a series of keys, and a normally locked accounting element controlled thereby, of a 125 detent member having provisions for latching said keys in depressed position and for unlocking said accounting element when said detent is in key-latching position; an operating mechanism; and means for locking said 130

operating mechanism from operation when any key is in a partially depressed position.

3. In a keyboard mechanism for accounting machines and the like, the combination with a series of keys, and an accounting element controlled thereby, of a detent member having provisions for latching said keys in depressed position and for unlocking said accounting element when said detent is in key-latching position; an operating mechanism; and means for locking said operating mechanism from operation when any key is depressed to such an extent as to move said detent member sufficiently to unlock the accounting element without the attendant latching of the key.

4. In a keyboard mechanism for accounting machines and the like, the combination with a series of keys, and an accounting element controlled thereby, of a detent member having an extension normally engaging said accounting element to lock the same, said detent also being formed with beveled and notched projections acted upon by said keys to move the detent out of locking engagement with said accounting element while said detent at the same time latches the key in depressed position; an operating device; and means for locking said operating device when any key is partially depressed to disengage the detent member from said accounting element.

5. In a keyboard mechanism for accounting machines and the like, the combination with a series of keys, and an accounting element controlled thereby, of a detent member having an extension for normally locking said accounting element, said detent being positioned to be acted upon by said keys to be displaced a certain extent and then moved backward to a fractional degree thereof whereby to latch the depressed key in operated position and at the same time leave the accounting element unlocked; and means for preventing the operation of the machine when any key is in a partially depressed position.

6. In a keyboard mechanism for accounting machines and the like, the combination with a series of keys, and an accounting element controlled thereby, of a detent member having an extension for normally locking said accounting element, said detent being positioned to be acted upon by said keys to be displaced a certain extent and then moved backward to a fractional degree thereof whereby to latch the depressed key in operated position and at the same time leave the accounting element unlocked; an operating device; and a locking member connected with and moved by said operating device, with provisions for preventing the operation of said locking member and thus locking the operating device when any key is in partially depressed position.

7. In a keyboard mechanism for accounting machines and the like, the combination with a series of keys, and an accounting element controlled thereby, of a detent member having an extension for normally locking said accounting element, said detent being positioned to be acted upon by said keys to be displaced a certain extent and then moved backward to a fractional degree thereof whereby to latch the depressed key in operated position and at the same time leave the accounting element unlocked; an operating device; and a locking plate normally moved by said operating device, with provisions co-existing between said plate and said keys for obstructing the movement of the plate when any key is in partially depressed position whereby to lock said operating device.

8. In a keyboard mechanism for accounting machines and the like, the combination with a series of keys, and an accounting element controlled thereby, of a detent member having an extension for normally locking said accounting element, said detent being positioned to be acted upon by said keys to be displaced a certain extent and then moved backward to a fractional degree thereof whereby to latch the depressed key in operated position and at the same time leave the accounting element unlocked; an operating device; projections extending from said keys; and a locking plate co-operating with said projections and moved by said operating device, said plate being formed with recesses shaped to lock the plate and the operating device from movement when a key is partially depressed but to permit free movement of the plate and operating device when a key is undepressed or fully depressed.

9. In a keyboard mechanism for accounting machines and the like, the combination with a series of keys, each formed with projections extending therefrom, and an accounting element controlled by said keys, of a detent plate having an extension for normally locking said accounting element, said detent plate being formed with beveled surfaces co-operating with said key projections, and also being formed with latching recesses, said recesses being of such extent as to leave the detent plate displaced from normal position when any key is latched in depressed position, and thereby leaving the accounting element unlocked; an operating device; and a locking plate moved by said operating device and having provisions co-operating with the aforesaid key projections for locking the operating device when any key is in partially depressed position.

10. In a keyboard mechanism for accounting machines and the like, the combination with a series of keys, and an accounting element controlled thereby, of a detent member

having provisions for latching said keys in depressed position and for unlocking said accounting element; means for holding said accounting element in normal position independently of its control by said keys; and means for preventing the operation of the machine when any key is less than wholly depressed.

11. In a keyboard mechanism for accounting machines and the like, the combination with a series of keys, and an accounting element controlled thereby, of a detent member having provisions for latching said keys in depressed position and for unlocking said accounting element when said detent is in key-latching position; an operating mechanism; means operated by said operating mechanism for retaining said accounting element in normal position independently of its released condition by said keys; and means for locking said operating mechanism from operation when any key is depressed to such an extent as to move said detent member sufficiently to unlock the accounting element without the attendant latching of the key.

12. In a keyboard mechanism for accounting machines and the like, the combination with a series of keys, and an accounting element controlled thereby, of a detent member having an extension for normally locking said accounting element, said detent being positioned to be acted upon by said keys to be displaced a certain extent and then moved backward to a fractional degree thereof whereby to latch the depressed key in operated position and at the same time leave the accounting element unlocked; an operating device; and means for locking said operating device at the time when the detent member is being displaced to its greatest extent preparatory to its reverse movement for latching the depressed key.

13. In a keyboard mechanism for accounting machines and the like, the combination with a series of keys, and an accounting element controlled thereby, of a detent member having an extension for normally locking said accounting element, said detent being positioned to be acted upon by said keys to be displaced a certain extent and then moved backward to a fractional degree thereof whereby to latch the depressed key in operated position and at the same time leave the accounting element unlocked; an operating device; means for locking said operating device at the time when the detent member is being displaced to its greatest extent preparatory to its reverse movement for latching the depressed key; and independent means for locking said operating device while the key is in partially depressed position and the first-mentioned locking device has not become effective.

14. In a keyboard mechanism for account-

ing machines and the like, the combination with a series of keys, and an accounting element controlled thereby, of a detent member having an extension for normally locking said accounting element, said detent being positioned to be acted upon by said keys to be displaced a certain extent and then moved backward to a fractional degree thereof whereby to latch the depressed key in depressed position and at the same time leave the accounting element unlocked; an operating device; means for locking said operating device at the time when the detent member is being displaced to its greatest extent preparatory to its reverse movement for latching the depressed key; and a locking plate moved by said operating device and having provisions for locking the operating device when a key is partially depressed prior to the first-mentioned locking device becoming effective, said provisions also permitting the unobstructed movement of said locking plate by the operating device when a key is un-depressed or is in fully depressed position.

15. In a keyboard mechanism for accounting machines and the like, the combination with a series of keys, and an operating device, of a locking plate co-operating with said keys and controlling said operating device; means for moving said locking plate at each operation of said operating device; and means for obstructing the movement of said locking plate and thereby locking said operating device when any key is in partially depressed position.

16. In a keyboard mechanism for accounting machines and the like, the combination with a series of keys, and an operating device, of a locking member co-operating with said keys, a spring-pressed element connected with said locking member and operated upon by said operating device to actuate the locking member; and means also associated with said connections for locking said operating device when the locking member is obstructed by any partially depressed key.

17. In a keyboard mechanism for accounting machines and the like, the combination with a series of keys, and an operating device, of a locking plate having blocking provisions co-operating with said keys; a lever for reciprocating said plate; a spring-pressed pawl mounted upon said lever; an actuating cam connected with said operating device for acting upon said spring-pressed pawl to reciprocate said plate; and a locking projection extending from said lever to lock said operating device when the locking plate is blocked by a depressed key.

18. In a key board mechanism for accounting machines and the like, the combination with a series of keys, and an operating device, of means for blocking said device, but adapted to be moved from blocking position by said device, and a plate moved with said

blocking device, constructed to engage said keys when they are partially depressed and thereby prevent the moving of said blocking devices.

- 5 19. In a key board mechanism for accounting machines and the like, the combination with a series of keys, and an operating device, of blocking means for said operating device constructed to be moved out of the 10 path of said device, and means connected to said blocking device and constructed to engage said keys when they are partially operated to prevent movement of said blocking device.
- 15 20. In a key board mechanism for accounting machines and the like, the combination with a series of keys, of an operating device, means for blocking said operating device, a plate connected to said blocking means ar-

ranged to move past said keys, means connected to said operating device to withdraw 20 said blocking device from blocking position.

21. In a key board mechanism for accounting machines and the like, the combination with a series of keys, and a registering element controlled thereby, of means for locking said element constructed to be released by said keys, an operating device, and means for blocking said operating device when any of said keys is in partially depressed position. 25

In testimony whereof I affix my signature in the presence of two witnesses.

THOMAS CARROLL.
